CLAIM

The ornamental design for a beverage container, as shown and described.

DESCRIPTION

FIG. 1 is a perspective view of a beverage container showing my new design;

FIG. 2 is an exploded view thereof;

FIG. 3 is a front view thereof;

FIG. 4 is a top view thereof; and,

FIG. 5 is a bottom view thereof.

The broken lines in the drawing views represent environmental structure and form no part of the claimed design.
